WATER VAPOR REPLENISHER FOR GASEOUS DISCHARGE SWITCHING DEVICES

Harold Heins, Dorchester, Mass., assignor to Bamac Laboratories Inc., Beverly, Mass., a corporation of Massachusetts

Application September 6, 1952, Serial No. 308,211

2 Claims. (Cl. 313—180)

This invention relates to gaseous discharge switching devices and more particularly to means for replenishing a component of the gaseous medium employed in such devices.

Gaseous discharge switching devices are commonly employed in radio direction and range systems to permit the use of a single antenna and are referred to in the art as transmit-receive devices. Generally, such devices contain a gaseous medium under reduced pressure with a predetermined percentage of water vapor as a component thereof.

Water vapor is employed as a component of the gaseous medium as an electron capture agent. After cessation of a radio frequency discharge, free electrons remaining in the vicinity of the discharge gap cause a loss in intensity of the returned low level signal. It is therefore, necessary that these electrons be removed from the gap. Water vapor is an effective electron capture agent and causes the formation of negative water vapor ions. The relatively heavy negative water vapor ions, because of their low mobility, do not extract appreciable energy from the returning low level signal.

It has been observed experimentally in the art that after a certain period of operation the gas content is altered, principally by clean-up of the water vapor. At high power transmission levels the rate of clean-up of the water vapor appears to be a function of the power level.

In many applications of radio direction and range systems the rate of removal of free electrons is a determining factor in the minimum operating range and minimum target size. Clean-up of the water vapor is therefore, an important phenomena to be considered.

Accordingly, it is an object of this invention to provide in a gaseous discharge switching device means for replenishing the water vapor to increase operational life. It is a further object to provide means for replenishing the water vapor which will be operative at the point of installation of the gaseous discharge switching device.

In accordance with the teachings of my invention, I provide means for retaining a predetermined quantity of silicic acid in powder form within the envelope of a gaseous discharge switching device, or, if desired, said retaining means may be externally mounted and communicate with the envelope of the device. The silicic acid powder retaining means is heated to a temperature sufficient to cause the silicic acid powder to decompose into water vapor and silica. The water vapor will diffuse throughout the gaseous medium.

An advantage of the present invention is the ease of operation, thereby permitting an extension of life without the necessity of extensive maintenance at the point of installation.

The invention will be understood more clearly and fully from the following detailed specification and reference to the appended drawings, in which:

Figure 1 is an enlarged side elevation partly in section of an illustrative embodiment;

2

Figure 2 is a detailed vertical transverse section of a component of the invention;

Figure 3 is a detailed vertical transverse section of a modification of the present invention; and

Figure 4 is an enlarged side elevation of an alternative embodiment.

Referring to Figure 1, the glass reservoir 1 of a transmit-receive gaseous discharge device is shown communicating with the metal envelope 2. Positioned within and supported by this glass reservoir is an auxiliary electrode 3 with a dielectric sheathing 4. Electrode 3 may be provided with a top cap 5 for connection to a suitable voltage supply. At predetermined points, a portion of sheathing 4 may be removed to facilitate attachment of supporting rods 6 and 7, extending at right angles, to the core of electrode 3.

A sleeve 8, desirably of a refractory metal or ceramic, is affixed to rods 6 and 7 by conventional methods. One end of sleeve 8 may be crimped as shown at 9. The open end of sleeve 8 is packed with a perforate material 10. In the preferred embodiment, I have found quartz wool to be desirable.

A coil of an insulated heater wire 11 surrounds sleeve 8 as shown. One end of said heater coil is connected to supporting rod 7, as at 12, while the other end is connected to a tab 13 which may be sealed through glass envelope 1. A top cap 14 may be provided as a lead for a voltage supply shown at 15.

In detail as shown in Figure 2, sleeve 8 is closed at one end as at 9. A quantity of silicic acid powder 16 is contained within said sleeve. A tight pack of quartz wool 10 is provided at the open end.

A modification of the present invention as shown in Figure 3, provides a perforated powder retaining sleeve 18, with top and bottom sections 19 and 20. Supporting rods 21 and 22 are attached to sleeve 18, and may be affixed to the core 3 of an electrode as shown in Figure 1. A tube 23 is positioned axially within sleeve 18 and may be supported by the top and bottom sections. A coil of insulated heater wire 24 extends within tube 23 and is connected to supporting rod 22 and an external connection, substantially as shown in Figure 1. The silicic acid powder is retained with sleeve 18 as shown at 16.

In Figure 4, I have shown an alternative embodiment of the present invention which may be employed in devices without an auxiliary electrode or antitransmit-receive devices, commonly found in radar systems to disconnect the ultra high frequency generator from the antenna when a returning signal is received.

In this embodiment, metal envelope 25 may be provided with a glass envelope 26 communicating with the gaseous atmosphere enclosed by the metal envelope. A supporting rod 27 with two members 28 and 29 extending at right angles thereto, support sleeve 30 in a manner substantially similar to that shown in Figure 1.

By heating the powder retaining sleeve to a temperature of approximately 1000° C. with a suitable voltage supply, the silicic acid powder will decompose into water vapor and silica. The water vapor diffuses into the gaseous atmosphere through the quartz wool shown in Figures 1 and 2, or the perforated sides in Figure 3.

In the practice of this invention, a quantity of five milligrams of silicic acid powder heated to approximately 1000° C. for three minutes gave a yield of approximately 56 hundredths of a milligram of water vapor.

While I have shown and described several embodiments of this invention, its teachings may be practiced in various modifications of gaseous discharge switching devices employing water vapor, such as pre-transmit-receive, anti-transmit-receive, and band pass transmit-receive devices.

70 What I claim and desire to secure by Letters Patent is:

1. A gaseous discharge switching device comprising a

hermetically sealed enclosure, an ionizable atmosphere within said enclosure, an electrode extending axially within said enclosure, a plurality of spaced transverse support members mounted at an intermediate point on said electrode, a container supported by said transverse members parallel with said electrode, a quantity of silicic acid powder within said container, a heater coil encircling said container with a leg thereof electrically connected to a transverse support member and the opposite leg extending outside said enclosure for external circuit connection, said heater coil when energized adapted to heat said powder to a temperature of approximately 1000° C. to thereby introduce water vapor into said atmosphere.

2. A gaseous discharge switching device comprising a hermetically sealed enclosure including a metallic envelope and a dielectric bulb member externally mounted thereon, an ionizable atmosphere within said enclosure, a wire conductor extending axially within said bulb member, a pair of spaced transverse support members mounted at an intermediate point on said conductor, a hollow member of a high temperature resistant material mounted parallel with said conductor and supported within said bulb member by said transverse members, a heater coil
